UNITED STATES PATENT OFFICE.

SAMUEL AIKINS, OF WESTON, ONTARIO, CANADA, ASSIGNOR OF ONE-HALF TO ACHILLE A. PINARD, OF OTTAWA, ONTARIO, CANADA.

BASE FOR HOT-AIR FURNACES AND HOT-WATER AND STEAM BOILERS.

1,218,824.

Specification of Letters Patent. Patented Mar. 13, 1917.

Application filed March 20, 1916. Serial No. 85,382.

To all whom it may concern:

Be it known that I, SAMUEL AIKINS, a citizen of the Dominion of Canada, residing at Weston, in the county of York and Province of Ontario, Canada, have invented certain new and useful Improvements in Bases for Hot-Air Furnaces and Hot-Water and Steam Boilers, of which the following is a specification.

10 This invention relates to furnace bases and is so designed as to be readily adapted to fit under any of the standard makes of hot-air furnaces, circular hot-water and steam boilers.

15 In the present invention I show three distinct features: first, a combustion chamber without any grates on which to hold the coal or other fuel, second, a lower cold air receiving chamber around on the outer side 20 of the combustion chamber to pre-heat the air which is drawn from the house before entering the combustion chamber, third, an upper humidifying chamber over the cold air receiving chamber, and having automatically controlled supply pipes, with funnel-shaped tops to provide for exposing extended surfaces of water over which the air passes.

25 The object of my invention is to provide a base which will aid in combustion, add greater humidity to the heated air passing from the furnace and at the same time do away with all grates in the combustion chamber.

30 With this and other objects in view, the invention consists in the construction, combination and arrangement of parts as will be hereinafter fully described, illustrated in the accompanying drawing, and pointed out 35 in the claims hereunto appended.

In the drawing:

Figure 1 shows a perspective view of my invention, partly broken away.

Fig. 2 shows a plan view with the top 45 removed.

Fig. 3 shows a sectional view on line 3—3 of Fig. 2.

Fig. 4 shows a sectional view on line 4—4 of Fig. 2.

50 Similar reference characters indicate corresponding parts throughout the several views in the drawing.

5 designates an outer cylindrical wall having a flat bottom 6. These are preferably

formed of steel sheeting. 7 and 8 are doors 55 closing openings in the outer wall 5. These doors are opposite each other and situated with their bottom even with the bottom of the combustion chamber hereinafter mentioned. These doors are for removing ashes. 60

9 is an inner cylindrical wall, which is lined with two rows of fire bricks 10 and 11, the bricks being on their ends. Between the rows of bricks 10 and 11, I provide metal or brick arched members 12 providing openings 13. The wall 9 has semi-circular openings 14 registering with openings 13. Opposite door 7 is an opening 15 through the wall 9 and fire-bricks 11 and a similar opening 16 is opposite door 8. 70

The space between the outer wall 5 and the inner wall 9 is divided into two chambers 17 and 18 by a diaphragm 19 which is held in position by means of riveting to the walls 5 and 9. A plate 20 covers the 75 top of the chamber 18. The chambers 17 and 18 will be air-tight, but for the intake pipe and exhaust pipe, which will herein-after be explained.

The chamber 17 is called a cold air receiving chamber and has an intake pipe 21 entering through the wall 5 near the bottom. This pipe 21 can be suitably connected to piping connecting with a room of the house to draw off the cold air into the chamber 17 where it gets pre-heated before going through the openings 14 and 13 into the combustion chamber. 80

Coal takes from 200 to 300 cubic feet of air to each pound of coal consumed for 90 proper combustion. In the ordinary furnaces the cold air from the house is drawn into the combustion chamber and when it strikes the live coals it deadens them but in my invention, I provide a pre-heating 95 of the cold air from the house before it enters the combustion chamber and thus a much greater heat is derived. This is one of the important points of this invention, as it will greatly reduce the amount of fuel 100 used to give off the desired amount of heat.

The chamber 18 is called a humidifying chamber and has an intake pipe 22 entering through the wall 5 just above the diaphragm 19. Another pipe 23 enters through 105 the wall 5 near the top of chamber 18. Pipe 23 is an exhaust pipe.

24 is an annular piping having a closure

cap 25 screwed on one end. The other end screws into an elbow 26, having a connection 27 through the wall 5, which connects to a controller 28. The annular piping 24 5 has upwardly extending pipes 29 screwed in its upper side. Pipes 29 have funnel-shaped upper ends 29' and as these pipes hold water, it will be seen that the funnel-shaped top allows a larger expanse of water 10 to come in contact with the air in chamber 18. The controller 28 has a water feed supply pipe 30 connected to it, having cock 31 thereon. 32 is an ordinary shut-off valve which controls the intake of the water from 15 supply pipe 30, so that the height of the water in the container 33 will stay at a level slightly lower than the top of the upper funnel-shaped ends of the pipes 29. 40 is an over-flow pipe, which extends up into 20 the container 33. The top of this over-flow pipe 40 is slightly below the tops of the pipes 29. If the shut-off valve 32 should not work, the water will over-flow through pipe 40 instead of going into the humidifying 25 chamber and overflowing from pipes 29.

The pipe 22 extends through the cellar wall and draws pure, fresh, cold air from outside into the chamber 18 where it is brought to a temperate heat and the water 30 in the pipes 29 humidifies this air before it passes off through exhaust pipe 23 to be distributed through the house.

In most furnaces there is a water pan which is manually filled with water. The 35 inner end of the pan extends into furnaces to come in contact with the live heat and the humidity of the heated air is much denser than it should be. The water is soon all taken up and then the air passes through 40 the furnace without being humidified. This shows the two extremes that are constantly found with the ordinary manually filled water pan. With my invention relating to 45 humidifying the air, I bring the pure, fresh, cold air from the outside atmosphere, which will not be readily heated to an extreme heat in the chamber 18 before passing off through the house. In this temperate heat it takes up a moderate amount of moisture 50 and as the water supply is automatically controlled this humidifying is constantly going on, and thus the air in the house is kept at the same humidity. The greater the heat the greater the velocity of the air 55 in chamber 18, thus it will be seen that my invention keeps the humidity the same even with the change of heat in the combustion chamber. This is a very important part of 60 this invention as it will be found much more healthy for living.

There is no grate, but the fuel lies on the fire brick bottom 35 shown in Fig. 2.

The container 33 is preferably an ordinary glass fruit jar and by standardizing 65 this container in this way if it gets broken,

there is generally another around the house to put on or one can be had at the corner store.

From the foregoing it is thought that the construction of my invention will be clearly 70 understood, and therefore a more extended explanation has been omitted.

What I claim as new, is,

1. A furnace base, consisting of a combustion chamber, a cylindrical outer wall 75 spaced from the wall of said combustion chamber, the space between said combustion chamber and said cylindrical wall being divided into two separate chambers by a diaphragm, the lower chamber being provided 80 with an air inlet pipe, said combustion chamber being provided with openings communicating with the space between said combustion chamber and said cylindrical wall, the upper chamber being provided 85 with an air intake pipe and an air exhaust pipe, a water pipe in said upper chamber bent to form a segment of a ring and having a screw cap closure at one end and the other end extending out through said cylindrical 90 wall, an automatic control at the extended end of said pipe, said control consisting of a container screwed to its base and having a shut-off valve inside with water connection to said valve, and an over-flow pipe, said 95 bent water pipe having upwardly extending branch pipes with their upper ends funnel shaped, and oppositely situated doors opening into said combustion chamber.

2. A furnace base, consisting of a combustion chamber, a cylindrical outer wall 100 spaced from the wall of said combustion chamber, the space between said wall and said combustion chamber being divided by a diaphragm, said combustion chamber being provided with openings communicating with the space between said outer wall and said combustion chamber, an air intake pipe opening into the lower portion of said 105 space and an air intake pipe and an air exhaust pipe connected with the upper portion of said space, said upper portion of said space having a bent piping therein, one end of said piping extending out through said outer wall, said piping having upwardly extending branches with funnel shaped upper 110 ends and located in said upper air space.

3. A furnace base, consisting of a combustion chamber, a cylindrical wall spaced 115 from the wall of said combustion chamber having a brick facing on its inner side, the wall of said combustion chamber having openings therearound and corresponding openings through said brick facing, the space between said outer wall and said combustion chamber being divided into two sections by a diaphragm, said diaphragm being above said openings, an inlet air pipe in said lower section and an inlet air pipe 120 in said upper section and an exhaust air pipe in said upper section.

- tion, said outer wall having a set of openings and doors arranged opposite to each other, said combustion chamber having corresponding openings opposite said openings in said outer wall, said upper section having a humidifying means consisting of a bent piping around above said diaphragm with one end capped and the other end extending out through said outer wall and carrying an automatic shut-off thereon with suitable water supply means thereto, and said piping having upwardly extending branch pipings with funnel shaped upper ends.
- 15 4. A furnace base, consisting of an outer wall, and an inner cylindrical wall having a brick facing said inner wall forming the side of a combustion chamber, said walls being spaced apart, said cylindrical wall and

said brick facing having alining openings, 20 the space between said outer wall and said inner wall being divided into two sections, the lower section having an air intake pipe adapted to connect with a suitable room in the house, the upper chamber being provided with a humidifying means, an intake pipe in communication with the atmosphere and connecting to said upper section, an exhaust pipe from said upper section adapted to lead to main parts of the house, a humidifying means in said upper section and oppositely situated doors in said combustion chamber.

Signed at Weston, this 26 day of February, 1916.

In testimony whereof I hereunto affix my signature.

SAMUEL AIKINS.
